[57] CLAIM

The ornamental design for a personal computer key-
board template for displaying operating instructions for
software program, as shown and described.

DESCRIPTION

FIG. 1 is a front, top and left side perspective view of a
personal computer keyboard template for displaying
operating instructions for software program showing
my new design, the book being opened, and the key-
board being shown in broken lines for illustrative pur-
poses only;

FIG. 2 is a top plan view thereof on an enlarged scale,
the book being closed;

FIG. 3 is a front elevational view thereof on an enlarged
scale;

FIG. 4 is a bottom plan view thereof on an enlarged
scale;

FIG. 5 is a left side elevational view thereof on an en-
larged scale;

FIG. 6 is a right side elevational view thereof on an
enlarged scale.

The little book, which is an integral part of the personal
computer keyboard template for displaying operating
instructions for software program, is securely attached
to the base of the template.

FIG. 1.

FIG. 2.

FIG. 3.

FIG. 4.
